SOLVENT REFINING OF HYDROCARBON OIL

Robert E. Manley, Beacon, N. Y., assignor to The Texas Company, New York, N. Y., a corporation of Delaware

Application March 7, 1932, Serial No. 597,141

8 Claims. (Cl. 196—13)

This invention relates to refining hydrocarbon oils by solvent extraction and to an improved process for carrying out the extraction.

The invention contemplates a continuous countercurrent process for extracting hydrocarbon oils, such as lubricating oils, kerosenes, naphtha fractions and the like, with a selective solvent liquid such as furfural, or a derivative thereof, for the removal of undesired constituents wherein the solvent is continuously recovered from the separated hydrocarbon fractions and recycled through the system for treating fresh oil. The invention is particularly adapted to the treatment of lubricating oil fractions derived from asphaltic, mixed-base or paraffin-base crude sources wherein it is desired to separate therefrom fractions of relatively high viscosity index which may be subsequently finished up by acid treatment and clay contacting to produce a superior lubricating oil product.

More specifically, my invention comprises continuously and countercurrently contacting hydrocarbon oil, such as a lubricating oil fraction, with furfural, forming a liquid portion comprising relatively high viscosity index oil and some dissolved solvent liquid, and another liquid portion comprising the major part of the solvent liquid together with dissolved hydrocarbons of relatively low viscosity index. The resulting liquid portions are separately treated with water which is miscible with the furfural under the influence of heat and thus adapted to displace the dissolved oil therefrom. The displaced oil constituents may then be withdrawn and the remaining mixture of furfural and water subjected to cooling in order to separate the water and recover the furfural for treating fresh oil.

While in some instances the separated oil fraction, comprising the relatively high viscosity index constituents, may be finished up by contacting with a solid adsorbent material, it is advantageous to subject the separated oil to treatment with mineral acid, thereby producing a product low in sulphur and carbon residue content and substantially free from oxidizable bodies which otherwise render lubricating oil products unstable during their use, particularly where they are subjected to relatively high working temperatures.

I have found that treatment of the oil with furfural renders the oil more susceptible to improvement upon subsequent acid treatment. The treatment of lubricating oil fractions with furfural, followed by acid treatment in accordance with the method of my invention, results in a

product containing much less carbon residue and sulphur than that of a product obtained from a similar source when treating with acid alone according to the usual practice. It seems that the furfural and acid each remove materials not readily attacked by the acid alone, or by the furfural alone, and therefore the combination of the two steps is of decided advantage in producing a product of superior quality.

It is believed that furfural exerts a solvent action upon the naphthenic-type bodies of the oil, or those constituents which are characterized by their steep viscosity temperature relationship. Thus, by extraction with furfural, the undesirable constituents of relatively low viscosity index may be removed, thereby producing a product of relatively high viscosity index or, in other words, having a low viscosity temperature susceptibility. The viscosity index herein referred to may be determined by the method of Dean and Davis published on pages 618—619 of the 1929 issue of Chemical and Metallurgical Engineering.

Mineral oil has, in the past, been treated with liquid sulphur dioxide for the purpose of removing certain unsaturated constituents including naphthenic bodies. However, liquid sulphur dioxide exerts a selective solvent action upon the various constituents of the oil only at relatively low temperatures, usually in the neighborhood of 0° F., or, in any case, well below 32° F.

Furfural, on the other hand, exerts a selective solvent action at temperatures well above 32° F. and, in fact, exerts a solvent action upon the naphthenic-type bodies, for example, at temperatures up to 200° F. and above, and at elevated temperatures there is substantially no solvent action upon the high viscosity index constituents, as would be the case with liquid sulphur dioxide. Extraction of the oil with furfural may, therefore, be carried out without chilling the oil, thereby avoiding the necessity of employing refrigeration; nor is it necessary to employ pressures above atmospheric as in the case of sulphur dioxide in order to maintain it in the liquid phase.

Furfural is of particular advantage in refining wax-bearing oils derived from paraffin or mixed-base crude sources and from which the wax constituents separate as solid hydrocarbons when the oil is cooled to a temperature of 75° F. or lower. The use of liquid sulphur dioxide is precluded in treating oil of this nature, since the temperature at which the sulphur dioxide exerts a selective solvent action is well below the congealation point of such oil.

In order to more clearly describe the invention, reference will now be made to the accompanying flow diagram, forming a part of this specification, which illustrates the method of treating hydrocarbon lubricating oil fractions with furfural.

I may start out, for example, with a lubricating oil fraction derived from an asphaltic or naphthalene-base crude source, such as a lubricating distillate derived from Columbia crude, which has the following characteristics:

Gravity A. P. I.	19.1
Per cent carbon residue	.26
Per cent sulphur	.32
Saybolt universal viscosity:	
At 100° F.	645
At 210° F.	57
Viscosity index	10

This oil is withdrawn from a storage tank 1 and is passed through a heater 2 wherein it may be heated to a temperature of from about 125° F. to about 200° F. The heated oil is then introduced to a mixing chamber 3 wherein it is brought into intimate contact with furfural partially saturated with material extracted during previous contact with oil during a subsequent stage of the treating process. The proportion of solvent to oil may, for the purpose of this example, be about one part of oil to one part of furfural. The resulting mixture of oil and furfural, including extracted material dissolved in the furfural, is continuously withdrawn from a central portion of the mixing chamber 3 and conducted to the middle portion of a settling chamber 4 advantageously of substantially greater volume than that of the mixing chamber 3, and wherein stratification occurs. Thus, at all times within the settling chamber 4, there exist three strata; the middle stratum comprising separating liquids, the upper stratum consisting of separated oil of relatively high viscosity index and a small amount of solvent in the oil, and the bottom stratum consisting of extracted bodies including those of relatively low viscosity index dissolved in a relatively large amount of solvent.

The upper stratum or layer is continuously decanted and conducted to the bottom of a succeeding mixing chamber 5. Fresh furfural is introduced to the upper portion of this mixing chamber wherein it is brought into intimate contact with partially-treated oil being received from the settling chamber 4.

The mixture of oil and furfural is continuously withdrawn from the middle portion of the mixing chamber 5 and conducted to the middle portion of the settling chamber 6 wherein stratification occurs in a manner similar to that in the settling chamber 4. The separated oil and associated solvent which may be referred to as the raffinate phase is withdrawn from the upper portion of this settling chamber for recovery therefrom of the solvent while the bottom layer comprising the bulk of the solvent together with dissolved matter and which may be referred to as the extract phase, is conducted to the bottom of the mixing chamber 3 wherein it is mixed with fresh oil entering the system as already described. The furfural, substantially completely saturated with extracted material, is withdrawn from the bottom of the settling chamber 4 and subjected to further treatment for the recovery of the solvent, in a manner similar to that of the treated oil portion mentioned above and which will now be described in detail.

The treated oil containing a small amount of

extract phase material consisting of furfural and extract oil constituents dissolved in the solvent, as removed from the top of the settling chamber 6, is conducted to a heater 7 wherein it is admixed with water and heated, under a pressure of about thirty or forty pounds, to a temperature of around 275° F. and then introduced to a settling chamber 8.

At temperatures around 200° F. water becomes completely miscible with furfural and becomes completely miscible therewith at about 275° F. so that the oil is displaced from the solution. This separation occurs in the settling chamber 8, the displaced oil accumulating as an upper layer, while the mixture of furfural and water collects in the bottom of the settling chamber. The separated oil is then withdrawn from the top of the settling chamber 8 into a receiver 9, and may contain small amounts of solvent which can be removed by distillation or during subsequent treatment.

As above indicated, the raffinate phase retains some of the furfural which has dissolved therein, some of the extract oil constituents or non-paraffinic bodies. Upon removal of the extraction solvent either by water displacement or by distillation these extract oil constituents or non-paraffinic bodies remain in the raffinate oil as impurities. They are not removed with the furfural during the displacement with water because of their insolubility in water and they are also not removed by distillation because they boil within the range of the constituents comprising the raffinate oil. These remaining impurities are therefore removed along with any remaining solvent during the subsequent acid treating step.

The hot mixture of furfural and water collecting in the bottom of the settling chamber 8 is continuously withdrawn and conducted through a cooler 10 wherein it is cooled to a temperature of around 80° F., at which temperature water is no longer miscible with the furfural. The cooled mixture is then introduced to a final settling chamber 11 to effect complete separation between the water and the furfural. The water is withdrawn from the upper portion of the settling chamber 11 and returned to the inlet of the heater 7, wherein it is admixed with a fresh incoming stream of treated oil and furfural.

In a similar manner the solution of extracted matter and furfural is conducted to a heater 12 wherein it is admixed with water and heated to a temperature of around 275° F., following which it is introduced to a settling chamber 13. From this separating vessel, the extracted material separated from the solvent by the water is withdrawn from the upper portion of the vessel to a receiver 14. The hot mixture of furfural and water is withdrawn from the bottom of the chamber 13 through a cooler 15 to a final settling chamber 16. The water separated from the furfural in this chamber is withdrawn therefrom and conducted back to the inlet of the heater 12.

The recovered furfural, substantially free from water and oil, collecting in the bottom of the settling chambers 11 and 16 is withdrawn therefrom and returned to the upper portion of the mixing chamber 5 wherein it is contacted with partially-treated oil as already described.

While only two pairs of mixing and settling chambers have been shown in which the oil is brought into countercurrent contact with the furfural, it is contemplated that any number of these chambers may be employed. Furthermore, it is desirable to employ a closed system to permit

carrying on the process under sufficient pressure to prevent vaporization of any of the liquids or materials entering into the process.

The solvent treated or separated oil collecting in the receiver 9 and the extract collecting in the receiver 14 will each have the following tests:

	Separated oil	Extract	
10 Gravity A. P. I.	22.1	12.8	
Per cent carbon residue	.14	.98	
Per cent sulphur	.17	.37	
Saybolt universal viscosity:			
At 100° F.	471	1285	
At 210° F.	54	63	
15 Viscosity index	39	Below 0	

The above separated oil is then subjected to treatment with sulphuric acid. When treating it with twenty pounds of 98% acid per barrel of oil, and then contacting the acid-treated oil with acid-treated clay in the proportion of twenty pounds of clay to the barrel and at a temperature of 450° F., the product will have the tests tabulated below. For the purpose of comparison, parallel tests are also submitted on a product obtained by subjecting a sample of similar original lubricating oil fraction to similar acid treatment and clay contacting but without the intermediate furfural treatment.

	Acid and clay-treated separated oil	Acid and clay-treated unseparated oil	
35 Gravity A. P. I.	22.7	19.7	
Per cent carbon residue	.05	.15	
Per cent sulphur	.14	.22	
Saybolt universal viscosity:			
At 100° F.	539	575	
At 210° F.	57	55	
40 Viscosity index	46	11	

It is seen, therefore, that the acid and clay-treated furfural extracted oil has a viscosity index of 46 with a carbon residue of .05, as compared with a viscosity index of 11 and a carbon residue of .15, in the case of a product which has not been subjected to previous extraction with furfural.

While the treatment of lubricating oil fractions derived from an asphalt-base source has been described in the foregoing example, the invention is not restricted to the treatment of this type and is equally well adapted to treating paraffin-base type oils as well as various mineral oil fractions.

55 Thus, the following example illustrates the results obtained when subjecting a paraffin distillate fraction to extraction with furfural followed by treatment with sulphuric acid. A dewaxed paraffin distillate fraction was subjected to countercurrent treatment at 200° F. with furfural in the ratio of two parts of furfural to one part of oil.

The tests on the oil, before and after treatment with furfural, were as follows:

	Before treatment with solvent	After treatment with solvent	
95 Gravity A. P. I.	21.7	26.1	
Percent carbon residue	.73	.37	
Percent sulphur	.58	.35	
Saybolt universal viscosity:			
At 100° F.	1110	770	
At 210° F.	81	70	
70 Viscosity index	65	73	

75 The solvent-refined oil was then treated with

five pounds per barrel of 98% sulphuric acid, resulting in an acid-treating loss of about 5% by volume. The acid-treated oil was then contact-filtered with twenty pounds per barrel of acid-treated clay to produce a decolorized and neutral product. The tests on the resulting acid-treated oil are submitted below together with comparative tests on a fraction obtained by subjecting a sample of similar original distillate to heavy acid treatment followed by neutralization with clay but without the intermediate solvent treatment:

	Combined solvent and acid treatment	Acid treatment only	15
Gravity A. P. I.	26.4	23.9	
Percent carbon residue	.16	.44	
Percent sulphur	.25	.44	
Saybolt universal viscosity:			
At 100° F.	675	898	20
At 210° F.	70	75	
Viscosity index	87	70	

This example demonstrates that the same marked improvement results when treating paraffin-base oil in accordance with the method of my invention.

The acid-treated clay employed in the foregoing examples was of the type disclosed in Chappell et al. Patent No. 1,642,871, and which has commonly been employed in recent years in decolorizing petroleum oils. While this type of adsorbent material is preferred, obviously other adsorbent materials may be employed, such, for example, as clays of the type of fuller's earth.

The method of my invention is particularly well adapted to the refining of naphtha or kerosene fractions with furfural, and from which treated fractions the furfural may be recovered by water displacement as above described.

Also the invention is not limited to any particular set of operating conditions since the temperatures, or the proportion of solvent to oil undergoing treatment, may be varied at will, depending on the characteristics of the desired final product.

Obviously many modifications and variations of the invention, as hereinbefore set forth, may be made without departing from the spirit and scope thereof, and therefore, only such limitations should be imposed as are indicated in the appended claims.

I claim:

1. The continuous process of refining a mineral lubricating oil fraction with furfural to produce lubricating oil of high viscosity index which comprises conducting the oil through a plurality of mixing and separating zones arranged in alternate succession, conducting a body of furfural therethrough countercurrently to the oil, alternately mixing together and then separating the countercurrently-flowing bodies of oil and furfural, the relatively saturated furfural coming into contact with relatively fresh oil, while the relatively finished oil comes into contact with fresh furfural, maintaining the bodies of oil and furfural at a temperature of about 200° F., forming one portion of liquid composed of furfural and dissolved material extracted from the oil and another portion composed of refined oil and a relatively small amount of furfural, separately heating said liquid portions in admixture with water to a temperature of about 275° F., at which temperature the water becomes miscible with the furfural and displaces the oil therefrom, settling

- the resulting mixtures while maintained in a heated condition to effect stratification and separation of the displaced oil constituents, removing the separated refined oil and the separated extracted matter, cooling the remaining mixtures of water and furfural to about 80° F. to effect separation of the water, returning the separated water for treating further solvent and dissolved oil, and returning the recovered furfural for extracting fresh oil.
2. The process of manufacturing relatively high viscosity index lubricating oil low in sulphur and carbon residue content from lubricating oil fractions derived from Gulf Coastal crudes and the like which comprises counter-currently extracting the fraction with furfural at a temperature of from 125° to about 200° F. to remove undesirable constituents including those characterized by low viscosity index, treating the solvent-extracted oil with a small amount of strong sulphuric acid to further remove undesirable constituents including sulphur and carbon-forming bodies, and contacting the acid-treated oil with solid adsorbent material to produce a neutral oil of good color.
3. The process of manufacturing relatively high viscosity index lubricating oil low in sulphur and carbon residue content from lubricating oil fractions derived from Gulf Coastal crudes and the like which comprise continuously and countercurrently extracting the fraction with furfural at a temperature of from 125° F. to about 200° F. thereby forming a body of extracted oil containing some dissolved furfural, heating this body of liquid in the presence of water to a temperature of about 275° F. to displace the oil from the solvent, returning the separated solvent for mixing with fresh oil, treating the resulting oil with sulphuric acid, and contacting the acid-treated oil with solid adsorbent material to produce a neutral oil of good color.
4. The process of preparing lubricating oil of relatively high viscosity index from mineral lubricating oil comprising treating the oil with furfural to extract the bulk of the undesired constituents and increase the susceptibility of the oil to further refining with mineral acid, subjecting the furfural-refined oil to treatment with a small amount of strong sulphuric acid whereby a product is produced having qualities including viscosity index characteristics superior to those obtained by treating the oil with either the solvent or acid alone, and thereafter neutralizing the acid-treated oil.
5. The process of preparing lubricating oil of relatively high viscosity index from mineral lubricating oil comprising treating the oil with fur-

fural to extract the bulk of the undesired constituents and increase the susceptibility of the oil to further refining with sulphuric acid, subjecting the furfural-refined oil to treatment with a small amount of strong sulphuric acid whereby a product is produced having qualities including viscosity index characteristics superior to those obtained by treating the oil with either the solvent or acid alone, and contacting the acid-treated oil with a solid adsorbent material to produce a neutral oil of good color.

6. In the manufacture of a finished lubricating oil of low carbon residue content and high viscosity index from mineral lubricating oil stock, the process comprising mixing the stock with furfural, separating the mixture into an extract phase containing relatively non-paraffinic oil of low viscosity index dissolved in the solvent and a raffinate phase comprising paraffinic oil of high viscosity index and retaining some of the extract phase, separating the two phases, removing the solvent from the raffinate phase and removing extract phase material remaining in the raffinate oil by treatment with about 98% sulphuric acid in the proportion of about 5 to 20 pounds of acid per barrel of oil.

7. In the manufacture of a finished lubricating oil of low carbon residue content and high viscosity index from mineral lubricating oil stock, the process comprising mixing the stock with furfural, separating the mixture into an extract phase containing relatively non-paraffinic oil of low viscosity index dissolved in the solvent and a raffinate phase comprising paraffinic oil of high viscosity index and retaining some of the extract phase, separating the two phases, removing extract phase material remaining in the raffinate oil by treatment with about 98% sulphuric acid in the proportion of about 5 to 20 pounds of acid per barrel of oil and finally contacting the acid-treated oil with a solid adsorbent material to produce a neutral oil of good color and low carbon residue content.

8. The process for preparing a lubricating oil of improved viscosity index from a viscous mineral lubricating oil distillate containing naphthenic and paraffinic hydrocarbons, and of the type derived from Mid-Continent crude, which comprises extracting the oil with a solvent containing furfural and thereby separating the highly naphthenic compounds from the paraffinic compounds, and then treating the highly paraffinic fraction with strong sulphuric acid in the proportion of about 5 pounds of acid per barrel of oil.

ROBERT E. MANLEY.
